(57) **CLAIM**

The new original and ornamental design for panel system, insect repellant, mildew resisting, refurbishable, as shown and described.

DESCRIPTION

FIG. 1 is a perspective view of panel system, insect repellant, mildew resisting, refurbishable

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top view thereof; and,

FIG. 7 is a bottom view thereof.

The broken line showing of environment is included for purpose of illustrating only and forms no part of the claimed design.

Figures shown broken away indicate indeterminate length.
